UNITED STATES PATENT OFFICE.

RAY S. HOYT, OF RIVER EDGE, NEW JERSEY, ASSIGNOR TO AMERICAN TELEPHONE AND TELEGRAPH COMPANY, A CORPORATION OF NEW YORK.

SIGNALING SYSTEM UTILIZING AS SIGNALING CHANNELS THE MINOR TRANSMITTING BANDS OF A LOADED LINE.

Application filed July 9, 1924. Serial No. 725,081.

One object of my invention is to provide appropriate signaling apparatus in combination with any loaded line to enable the minor transmitting bands of the loaded line 5 to be utilized as channels for signaling purposes (including any communication purposes or any operating purposes)—in addition to utilization of the major or principal transmitting band.

10 Another object is to provide a loaded line having transmitting bands of any desired locations and widths—not incompatible with inherent relations (set forth in due place in this specification).

15 (Throughout these specifications and claims the term "line" is used in a generic sense to include "cables" as well as "open-wire lines." The loading of the line may be wholly lumped, as in loading coils; or it 20 may be in part lumped, and in part distributed smoothly or uniformly, as by surrounding each line-wire with a material of high magnetic permeability—such as perm-alloy, for example.)

25 For the better understanding of the objects of my invention, certain preliminary remarks will be made regarding the minor transmitting bands, together with the major or principal transmitting band:

30 It is well-known, in the art, that a loaded line without any distributed inductance would have only one transmitting band and only one attenuating band; the former extending from zero frequency to the so-called 35 critical frequency, and the latter from the critical frequency to infinite frequencies—the "critical frequency" being the name given to the sharply defined transition frequency between the transmitting band and

40 the attenuating band of the corresponding non-dissipative loaded line. Actually, however, every line—even a cable—has some distributed inductance. But it is not generally known that the presence of distributed inductance in any loaded line whose loading is at least partly lumped introduces into the aforesaid attenuating band an infinite number of transmitting bands. These 45 additional transmitting bands, which usually are relatively narrow and located at relatively wide intervals, are herein termed the "minor" transmitting bands to distinguish them from the "major" or "principal" transmitting band—the name herein given

to the well-known relatively wide transmitting band of any loaded line (the first or lowest transmitting band). Since every natural line has some distributed inductance of its own, all of the bands are present when the loading is wholly lumped, as well 60 as when the loading is partly lumped and partly distributed smoothly.

Since a smooth line has a transmitting band extending from zero to infinite frequencies, an alternative statement is that the 65 application of lumped loading to a smooth line introduces into this pre-existing transmitting band an infinite number of attenuating bands.

As a result of a thorough-going theoretical study I have deduced general mathematical formulas by means of which the locations and widths of the minor transmitting bands can be calculated in the case of any given loaded line; or by means of 75 which a loaded line can be so designed that its minor transmitting bands will have any preassigned locations and widths—not incompatible with inherent relations. I am thus enabled to attain the aforesaid objects 80 of my invention.

My invention may now be more fully understood by means of the following description when read in connection with the accompanying drawings, of which Figure 1 85 represents schematically one end of a loaded line provided with signaling apparatus to enable several of the minor transmitting bands to be utilized, by means of carrier currents, as signaling channels—in addition to 90 utilization of the major transmitting band for ordinary telephonic and telegraphic purposes. Fig. 2 represents merely the loaded line itself, together with the mathematical symbols employed in this specification for 95 denoting the electrical constants thereof. Fig. 3 is a scale illustrating the relative locations and widths of the transmitting bands and attenuating bands of a loaded line, the quantity D being proportional to 100 the frequency. The heavily-drawn segments represent transmitting bands; the lightly drawn segments, attenuating bands. Fig. 4 is a set of mathematical curves which I have provided in order to facilitate determining 105 the locations of the transmitting bands of any given loaded line; and, on the other hand, to facilitate the designing of a loaded

line to have specified locations of its transmitting bands. Fig. 5 is a curve showing the locations and widths of the transmitting and the attenuating bands of a specific 5 loaded line chosen for illustrative purposes. The humps in the curve correspond to attenuating bands, and the valleys between correspond to transmitting bands or channels.

10 It will be recalled that the first mentioned object of my invention is to provide appropriate signaling apparatus in combination with any loaded line to enable its minor transmitting bands (besides its major transmitting band) to be utilized as channels for 15 signaling purposes. Fig. 1 illustrates how this object can be attained. It represents one end of such a system; the other end, not shown, would be similar or approximately 20 similar; connecting the two ends is a loaded line, only a small portion of which is shown in Fig. 1. The arrangement in Fig. 1 is such as to enable the utilization of six minor bands—two for telegraph transmitting; two for telegraph receiving, one for telephone transmitting, and one for telephone receiving—in addition to utilization 25 of the major transmitting band for ordinary telephone and telegraph purposes. The modulators, detectors, and amplifiers shown may be of any of the well-known types used in carrier telephony and telegraphy; the filters may be of the Campbell type. Although in existing loaded lines 30 none of the minor transmitting bands is wide enough to serve as a telephone channel, yet it is possible, by so designing the loaded line as to have a relatively large ratio of distributed inductance to coil inductance 35 (for instance, by application of smooth loading—in the form of permalloy, for example) to render one or more of the minor bands wide enough to serve as telephone channels. It is because of this possibility, contemplated 40 as one of the features in the second-mentioned object of my invention, that I have in Fig. 1 shown the utilization of some minor bands for telephonic purposes. In this connection it may be remarked that some of the 45 minor bands would, in some instances, be wide enough for more than one telegraph channel. Other bands could be used for various operating purposes.

Before presenting the salient facts and 50 formulas pertaining to the locations of the minor transmitting bands it seems advisable to state the precise meanings of the terms "transmitting band" and "attenuating band": In the limiting case of no dissipation 55 a line having lumped loading, in addition to smoothly distributed inductance, would have sharply demarcated frequency-ranges of zero attenuation, and other frequency-ranges of non-zero attenuation—the former 60 termed transmitting bands, and the latter

attenuating bands. But no actual line is entirely non-dissipative; and the presence of dissipation introduces some attenuation into the transmitting bands and rounds out their sharp corners, thus somewhat obscuring 70 the transition frequencies. Hence for an actual dissipative loaded line the transition frequencies, and therewith the transmitting and the attenuating bands, are defined as meaning those of the corresponding non-dissipative loaded line. That is, if A denotes the attenuation constant (real component of the propagation constant $\Gamma = A + iB$) of the corresponding non-dissipative loaded line, then the transmitting bands are defined 80 to be the frequency-ranges in which $A = 0$, and the attenuating bands the frequency-ranges in which $A \neq 0$.

This mode of definition is similar to the familiar procedure adopted in defining the "critical frequency" of a loaded line as meaning the critical frequency that the same line would have if non-dissipative. (The "critical frequency" is the usually employed term for the transition frequency constituting the 90 upper boundary point of the only transmitting band usually recognized—namely, the first or lowest transmitting band, herein termed the major transmitting band.)

The salient facts and formulas pertaining to the locations of the transmitting bands (and the intermediate attenuating bands) will next be presented; but, to avoid digressions, the derivations of the formulas will be deferred to the latter part of the specification—just preceding the claims.

The fundamental mathematical symbols pertaining to the loaded line have the meanings indicated in Fig. 2: s denotes the spacing of the loading coils, and L' the inductance of each loading coil. L_1 and C_1 denote the smoothly or uniformly distributed line-inductance and line-capacity per unit length, so that sL_1 and sC_1 are the inductance and capacity of each line-segment between loading coils. γ denotes the ratio of line-segment inductance sL_1 to loading coil inductance L' , that is,

$$\gamma = sL_1/L'. \quad (1)$$

f denotes the frequency; and $\omega = 2\pi f$. 115 As already remarked, the smoothly distributed inductance L_1 may consist partly of artificial smooth loading, in addition to the natural inductance L_{11} of the line itself.

The general features pertaining to the locations and widths of the transmitting and the attenuating bands of a loaded line are represented on the D-scale in Fig. 3; D is proportional to the frequency, and has the 120 value defined by the equation

$$D = \pi fs\sqrt{L_1 C_1} = \pi f\sqrt{\lambda L' s C_1}. \quad (2)$$

As represented by Fig. 3, a loaded line has an infinite sequence of alternate transmitting and attenuating bands, beginning 130

with a transmitting band. (The transmitting bands are drawn heavy, the attenuating bands light.) The first transmitting band is the one that is herein termed the major or principal transmitting band because it is much wider than any of the succeeding transmitting bands and is the band regularly utilized for signaling purposes. The remaining transmitting bands are the ones herein termed the minor transmitting bands.

It is convenient to employ the term "compound band" to denote the band consisting of a transmitting band and the succeeding attenuating band. For any specific loaded line, the widths of all the compound bands are equal; though the transmitting bands become continually narrower with increasing frequency, and the attenuating bands 20 become continually wider—while their sum is constant. The D-width of each compound band has the simple value $\pi/2$.

In Fig. 3, the compound bands are numbered 1, 2, 3, ..., n , ... Thus, D_n denotes the transition value of D within the n th compound band; that is, D_n is the value of D at the transition point between the n th transmitting band and the n th attenuating band. $D_{n-1,n}$ denotes the transition value of D between the $(n-1)$ th and n th compound bands; and hence denotes the transition value of D between the $(n-1)$ th attenuating band and the n th transmitting band. Thus $D_{n-1,n}$ and D_n are respectively the low-

$$D_n = d_n + \frac{\lambda}{d_n} - \frac{1}{d_n} \left(\frac{\lambda}{d_n} \right)^2 + \left(\frac{2}{d_n^2} - \frac{1}{3} \right) \left(\frac{\lambda}{d_n} \right)^3 - \left(\frac{5}{d_n^3} - \frac{4}{3d_n} \right) \left(\frac{\lambda}{d_n} \right)^4 + \left(\frac{14}{d_n^4} - \frac{5}{d_n^2} + \frac{1}{5} \right) \left(\frac{\lambda}{d_n} \right)^5 - \left(\frac{42}{d_n^5} - \frac{56}{3d_n^3} + \frac{23}{15d_n} \right) \left(\frac{\lambda}{d_n} \right)^6 + \dots \quad (10)$$

valid for $n=2, 3, 4, \dots$ but not for $n=1$. For the case of $n=1$, so that $D_n=D_1$, the

$$D_1 = \sqrt{\lambda} \left(1 - \frac{\lambda}{6} + \frac{11\lambda^2}{360} - \frac{17\lambda^3}{5040} - \frac{281\lambda^4}{604800} + \frac{44029\lambda^5}{119750400} \dots \right). \quad (11)$$

The smaller λ , the more convergent are these formulas. Formula (11) is highly convergent, even when λ is as large as unity or even considerably larger. Formula (10) is much less convergent than (11) but is satisfactorily convergent when λ is a small fraction: or, stated more generally, when λ/d_n is small. In the next paragraph is given a widely applicable formula of successive approximation for D_n valid for all the values of n including $n=1$, and suitable even for large values of λ .

With D_n-d_n denoted by τ_n , a formula of successive approximation for τ_n is

$$\tau''_n = \frac{\lambda\tau'_n + \lambda \sin \tau'_n \cos \tau'_n - d_n \sin^2 \tau'_n}{\lambda + \sin^2 \tau'_n}. \quad (12)$$

τ'_n denotes an approximate known value of τ_n ; the formula yields a higher order ap-

er and upper boundary points of the n th transmitting band.

With regard to the n th compound band it will be noted that there are two kinds of transition points—namely the internal transition point D_n , and the external or boundary points $D_{n-1,n}$ and $D_{n,n+1}$.

The D-width of each compound band being $\pi/2$, the boundary points of the n th compound band have the simple values

$$D_{n-1,n} = (n-1)\pi/2, \quad (3) \quad 45$$

$$D_{n,n+1} = n\pi/2; \quad (4)$$

and hence, by (2), the corresponding boundary frequencies have the values

$$f_{n-1,n} = (n-1)/2s\sqrt{L_1 C_1}, \quad (5) \quad 50$$

$$f_{n,n+1} = n/2s\sqrt{L_1 C_1}. \quad (6)$$

The location of the internal transition point D_n of D within the n th compound band has no such simple formula as have the external or boundary points $D_{n-1,n}$ and $D_{n,n+1}$; for D_n is a root of a transcendental equation, namely,

$$D_n \tan (D_n - [n-1]\pi/2) = \lambda; \quad (7) \quad 55$$

and hence D_n can be expressed only in an infinite series of terms or of operations. In particular (for $n=1$),

$$D_1 \tan D_1 = \lambda. \quad (8) \quad 60$$

With $D_{n-1,n}$ denoted, for brevity, by d_n , so that

$$d_n = D_{n-1,n} = (n-1)\pi/2, \quad (9)$$

a power series formula for D_n is

appropriate power-series formula is

proximate value τ''_n in terms of τ'_n and the known quantities λ and d_n . τ''_n , in turn, 90 may be used in the formula in order to calculate a still more accurate approximate value τ'''_n ; and so on, until the last computed value of τ_n agrees as closely as necessary with the computed value just preceding 95 it. Of course, the more accurate is the approximate value constituted by τ'_n the fewer will be the applications of (12) necessary to compute τ_n to the required accuracy. First 100 approximation values for τ_n are represented by the formulas:

$$\tau'_n = \frac{\lambda}{d_n} \left(1 - \frac{\lambda}{d_n^2} \right) \text{ when } n \neq 1, \quad (13)$$

$$\tau'_n = \sqrt{\lambda} (1 - \lambda/6) \text{ when } n = 1, \quad (14) \quad 105$$

as can be seen from formulas (10) and (11)

respectively. When $n=1$, $\tau_n=D_1$, since $d_1=0$ by (9).

Another formula of successive approximation for τ_n is

$$\tau''_n = \tan^{-1} \frac{\lambda}{d_n + \tau'_n}, \quad (15)$$

but not convergent for $n=1$ unless λ is very small.

By means of the preceding formulas (10), (11), (12), (15), I have computed the curves, in Fig. 4, of

$$\tau_n \equiv D_n - D_{n-1,n}$$

as function of λ with n as parameter, covering a wide range of λ and the first eight values of n . Since

$$D_{n-1,n} = (n-1)\pi/2,$$

the value of D_n is immediately obtainable from

$$D_n = \tau_n + (n-1)\pi/2.$$

For still larger values of n the approximation (13)—or even the simpler approximation

$$\tau'_n = \lambda/d_n -$$

yields highly accurate values of τ_n .

D_n having been evaluated, the transition frequency f_n between the n th transmitting band and the n th attenuating band is, by (2), calculable immediately from

$$f_n = D_n/\pi s \sqrt{L_1 C_1}, \quad (16)$$

valid for all the values of n , that is, for $n=1, 2, 3, \dots$. In particular, the critical frequency f_1 (namely, the lowest transition frequency, that is, the frequency constituting the upper boundary point of the first or major transmitting band) has the value

$$f_1 = D_1/\pi s \sqrt{L_1 C_1}. \quad (17)$$

If f'_1 denotes the value of f_1 in the limiting case of no distributed inductance ($L_r=0$, so that $\lambda=0$), then

$$f'_1 = 1/\pi \sqrt{s C_1 L'}, \quad (18)$$

by (17), (1), and (11); for (11) shows that

$$D_1/\sqrt{\lambda}$$

approaches 1 when λ approaches 0.

As already stated, the mathematical proofs of the formulas and statements hereinbefore set down will be furnished in the latter part of this specification, preceding the claims.

The foregoing formulas and graphs enable the locations and widths of the transmitting bands of any loaded line to be computed; and, on the other hand, enable a loaded line to be so designed as to have transmitting bands of preassigned locations

and widths—so far as compatible with inherent relations. Such applications of the formulas will now be illustrated, after summarizing the inherent relations just referred to.

One inherent relation—represented in Fig. 3—has already been brought out, namely, that the widths of all the compound bands are equal; hence that the distances between the lower edges of all transmitting bands are equal.

Another inherent relation—also represented in Fig. 3—is that the transmitting bands grow narrower and narrower with increasing frequency—whence the attenuating bands grow wider and wider.

The external or boundary transition frequencies $f_{n-1,n}$ and $f_{n,n+1}$ of the n th compound band (any compound band), depend on only one parameter—namely, the product $s^2 L_1 C_1$. The internal transition frequency f_n depends on two independent parameters—namely the product $s^2 L_1 C_1$ and the ratio

$$\lambda \equiv s L_1 / L'$$

Thus, fixing $s^2 L_1 C_1$ fixes all of the external transition frequencies; fixing

$$s^2 L_1 C_1 \text{ and } \lambda \equiv s L_1 / L'$$

fixes all of the transition frequencies—external and internal. Fixing any one external transition frequency fixes $s^2 L_1 C_1$ and thereby fixes all of the remaining external transition frequencies; fixing any two transition frequencies of which at least one is an internal transition frequency fixes

$$s^2 L_1 C_1 \text{ and } \lambda \equiv s L_1 / L'$$

and thereby fixes all of the remaining transition frequencies—external and internal.

The relative widths of all of the bands (transmitting bands and attenuating bands) depend on only one parameter—namely, the ratio

$$\lambda \equiv s L_1 / L'$$

Thus, fixing

$$\lambda \equiv s L_1 / L'$$

fixes the relative widths of all the bands. Fixing the ratio of the widths of any two bands not both of which are compound bands fixes

$$\lambda \equiv s L_1 / L'$$

and thereby fixes the relative widths of all the bands.

In Fig. 3 the transmitting bands are represented as being relatively narrow compared with the attenuating bands. With existing loaded lines, this is indeed the case, but it is not an inherent relation: for any number of the transmitting bands can be made wider than the associated attenuating

bands by so designing the loading (lumped or smooth or both) as to secure a sufficiently large value of the ratio

$$\lambda \equiv sL_1/L'.$$

5

(However, for any fixed loading, there is some frequency beyond which the transmitting bands are narrower than the associated attenuating bands.)

- 10 To illustrate the first-mentioned object of my invention, suppose there is given a loaded line of specified constants and that it is desired to provide appropriate signaling apparatus in combination with this line
 15 to enable the minor transmitting bands—in addition to the major transmitting band—to be utilized as transmitting channels for signaling purposes. The fundamental step is to determine the locations and widths of
 20 the transmitting bands, and this can be accomplished by means of the formulas and curves already furnished in this specification.

As a first illustrative example I have
 25 chosen a very lightly loaded open-wire line having the following values of capacity, inductance, and loading coil spacing:

$$C_1 = .00835 \times 10^{-6} \text{ farad per mile.}$$

$$L_1 = .00367 \text{ henry per mile,}$$

$$30 L' = .0578 \text{ henry,}$$

$$s = 15.76 \text{ miles,}$$

$$\lambda \equiv sL_1/L' = 1.$$

The following table shows the locations and widths of the first eight transmitting bands of this loaded line.

<i>n.</i>	τ_n	$D_{n-1,n}$	D_n	$f_{n-1,n}$	f_n	$f_n - f_{n-1,n}$	$(f_n - f_{n-1,n})/f_n$
40 1	.8604	0	.8604	0	3,140	3,140	1.000
2	.4579	1.5708	2.0287	5,732	7,403	1,671	.532
3	.2840	3.1416	3.4256	11,464	12,500	1,036	.330
4	.2008	4.7124	4.9132	17,196	17,929	733	.234
5	.1541	6.2832	6.4373	22,928	23,490	562	.179
6	.1247	7.8540	7.9787	28,660	29,115	455	.145
7	.1046	9.4248	9.5294	34,392	34,774	382	.122
8	.0900	10.9956	11.0856	40,124	40,452	328	.105

45

This table was computed by means of formulas (3), (12), (11), (5), (16) before the general curves in Fig. 4 had been constructed. With Fig. 4 available, such tables
 50 can be constructed with relatively little labor.

- The numbers in the first column of the foregoing table are merely the designation numbers of the first eight compound bands.
 55 It will be recalled that a compound band consists of a transmitting band and the immediately succeeding attenuating band; for instance, the first compound band ($n=1$) consists of the first or major transmitting band and the first attenuating band—immediately following. The numbers in the columns headed $f_{n-1,n}$ and f_n are the transition frequencies constituting respectively the lower and the upper boundary points of
 60 the transmitting bands; and the numbers
 65

in the column headed $f_n - f_{n-1,n}$ are therefore the widths of the transmitting bands. The last column represents the relative widths of the transmitting bands, referred to the first or major transmitting band—⁷⁰ whose width is $f_1 - 0 = f_1$.

Fig. 5 gives a graph of the attenuation constant Γ (per periodic interval) of this loaded line as a function of the frequency, for the limiting case of no dissipation; it ⁷⁵ thereby depicts not only the locations and widths of the transmitting bands ($\Gamma=0$), but also the magnitude of the attenuation in the attenuating bands, and thus furnishes a basis of information for providing appropriate signaling apparatus in combination with the given loaded line for utilizing its various transmitting bands. This graph was computed by means of equation (26). The effect (not shown) of dissipation in the ⁸⁰ loaded line is, of course, to introduce some attenuation into the transmitting bands—an effect well-known as regards the first or major transmitting band. A detailed numerical study made by me, by means of the ⁸⁵ general formula (22) for the propagation constant

$$\Gamma = A + iB,$$

has shown that the attenuation in the succeeding transmitting bands increases progressively. In practical applications this fact might render desirable the employment of correspondingly more powerful amplifiers in the succeeding transmitting bands, ⁹⁰ or even the employment of attenuation equalizers.

Before leaving this illustrative example, it may be remarked that the above tabulated values of τ_n and D_n are not restricted to this particular loaded line but pertain to any loaded line having λ equal to unity—since ⁹⁵ τ_n and D_n depend only on λ . Likewise the graphed values of Γ , when plotted as a function of D instead of f , pertain to any loaded line having $\lambda=1$ —since, by (26), Γ depends only on D and λ . By (2), D is directly proportional to f . In particular, the tabulated values would hold for a cable having the same constants per periodic interval as ¹⁰⁰ the contemplated loaded open-wire line; that is, for a cable having a combination of lumped and smooth loading as follows:

$L' = .0578 \text{ henry} = \text{inductance of each loading coil,}$ ¹¹⁰

$L = .0578 \text{ henry} = \text{inductance of each line-segment between loading coils,}$

$C = .1316 \times 10^{-6} \text{ farads} = \text{capacity of each line-segment between loading coils.}$

If $C_1 = .062 \times 10^{-6} \text{ farads per mile}$, which is ¹²⁵ representative of its value in actual cables, then the loading coil spacing would be

$$s = C/C_1 = 2.12 \text{ miles.}$$

Hence $L_1 = L/s = .0272 \text{ henry per mile}$; and ¹³⁰

thus the smooth loading (obtained by means of permalloy, for instance) would be about .0262 henry per mile, since the natural inductance L_{11} of cable is about $L_{11} = .0010$ henry per mile.

As a second illustrative example I have chosen the same open-wire line but heavily loaded, with coils of much larger inductance and more closely spaced, as follows:

10

$$L' = 0.241 \text{ henry}, \\ s = 7.88 \text{ miles.}$$

C_1 and L_1 have the same values as in the first illustrative example; but now $\lambda = 0.12$.

15 The following table corresponds to that of the first example, except that it has not been carried farther than the fifth band.

n	r_n	$D_{n-1,n}$	D_n	$f_{n-1,n}$	f_n	$f_{n-1,n}$	f_n	$f_{n-1,n}$
1	3396	0	0.3306	0	2,479	2,479	1,000	
2	.0729	1.5708	1.6437	11,464	11,996	532	0.215	
3	.0377	3.1416	3.1793	22,928	23,203	275	0.111	
4	.0253	4.7124	4.7377	34,392	34,577	185	0.074	
5	.0190	6.2832	6.3022	45,856	45,995	139	0.056	

20 Comparison of this table with the first shows the great diversity between the two illustrative examples: The minor transmitting bands of the second example are much narrower and located at much higher frequencies than in the first example.

25 It will be recalled that the second-mentioned object of my invention is to provide a loaded line having transmitting bands of any desired locations and widths—not incompatible with the inherent relations, already set forth. It will be remembered that the inherent relations are such that only two transition frequencies may be arbitrarily specified, and that at least one of these must be the upper boundary frequency of a transmitting band. Because of its practical importance, it would usually be desired to specify the value of the critical frequency f_1 ; compatibly with this, there could be specified the lower boundary frequency $f_{n-1,n}$ of the n th transmitting band, for any chosen value of n . Also, it would usually be desirable for the nominal impedance k to have a particular value; k being defined by the equation

$$k = \sqrt{(sL_1 + L') sC_1} \quad (19)$$

30 However, not every practical case presents enough undetermined constants or parameters to admit of imposing as many as three conditions; for instance, in cases C and D below, only two conditions can be imposed.

35 The equations fundamental for design-purposes are (19), (17), (5), (1), (8); of which (17) and (8) are particular forms of (16) and (7) respectively. Because of frequent use below for design-purposes, it may

here be noted that (17) divided by (5) gives

$$D_1 = (n-1)\pi f_1 / 2f_{n-1,n} \quad (20)$$

This and (8) together determine λ ; that is,

$$\lambda = \frac{(n-1)\pi f_1}{2f_{n-1,n}} \tan \frac{(n-1)\pi f_1}{2f_{n-1,n}} \quad (21)$$

For purposes of illustrating the second-mentioned object of my invention, I have chosen to present the following four cases:

Case A.— C_1 , L_1 , L' and s free; f_1 , $f_{n-1,n}$, and k specified.

This is the case where there is initially no existing line at all; a loaded line is to be built, and is to be so proportioned as to have specified values of f_1 , $f_{n-1,n}$, and k . The design-problem is to determine the requisite values for C_1 , L_1 , L' , and s in terms of f_1 , $f_{n-1,n}$, and k . The solution can be obtained as follows: Dividing (19) by (5) and then substituting $sL_1 = \lambda L'$ from (1) gives

$$L' = (n-1)k / 2f_{n-1,n} \sqrt{\lambda(1+\lambda)} \quad (1A)$$

25 λ is known from (21). Then $sL_1 = \lambda L'$ gives

$$sL_1 = \frac{(n-1)k}{2f_{n-1,n}} \sqrt{\frac{\lambda}{1+\lambda}} \quad (2A)$$

Finally, from (5) and (2A),

$$sC_1 = \frac{n-1}{2kf_{n-1,n}} \sqrt{\frac{1+\lambda}{\lambda}} \quad (3A)$$

30 It is seen from (2A) and (3A) that the data and requirements of this case do not determine C_1 , L_1 , and s individually; but, as might be expected, only sL_1 and sC_1 —namely the total inductance and total capacity of each line-segment between loading coils. Thus any one of the quantities C_1 , L_1 , s is free to be specified. In many practical instances, s would be fixed; then L_1 and C_1 would be determined forthwith by (2A) and (3A) respectively. In certain other instances, C_1 would be fixed; then s would be determined by (3A), and thereafter L_1 by (2A). Similarly when L_1 is fixed.

35 It will be recalled that L_1 represents the smoothly distributed requisite total inductance per unit length. If L_{11} denotes the natural distributed inductance per unit length, then the amount of artificial smooth loading to be applied (by means of permalloy, for instance) will be $L_1 - L_{11}$ per unit length.

Case B.— C_1 given; L_1 , L' and s free; f_1 , $f_{n-1,n}$, and k specified. This is the case of any given smooth line, (though more particularly a cable) having a given capacity C_1 , to be so loaded (with lumped loading and also smooth loading) as to have specified values of f_1 , $f_{n-1,n}$, and k . The design problem is to determine the requisite values of L_1 , L' , and s in terms of f_1 , $f_{n-1,n}$,

and k . The solution can be obtained as follows: Substituting $L' = sL_1/\lambda$ into (19), then multiplying (19) by (5), and finally solving for s gives

$$s = \frac{n-1}{2C_1 k f_{n-1,n}} \sqrt{\frac{1+\lambda}{\lambda}}. \quad (1B)$$

λ is known from (21). Next, (5) and (1B) give

$$L_1 = C_1 k^2 \lambda / (1 + \lambda). \quad (2B)$$

Then $L' = sL_1/\lambda$ gives, by means of (1B) and (2B),

$$L' = (n-1)k/2f_{n-1,n}\sqrt{\lambda(1+\lambda)}, \quad (3B)$$

with λ known from (21).

20 If L_{11} represents the smoothly distributed requisite total inductance per unit length, If L_{11} denotes the amount of distributed inductance per unit length possessed by the line originally, then the amount of smooth loading to be applied (by means of permalloy, for instance) will be $L_1 - L_{11}$ per unit length.

Case C.— C_1 and L_1 given, L' and s free; f_1 and $f_{n-1,n}$ specified.

This is the case of an existing smooth line (C_1, L_1 —of which L_1 may consist partly of smooth loading) to be so loaded with lumped loading as to have specified values of f_1 and $f_{n-1,n}$. The design-problem is to determine the requisite values for L' and s in terms of C_1, L_1, f_1 , and $f_{n-1,n}$. The solution can be obtained as follows:

Equation (5) gives immediately

$$s = (n-1)/2f_{n-1,n}\sqrt{L_1 C_1}. \quad (1C)$$

Substituting this value of s into (1) gives

$$L' = \frac{n-1}{2\lambda f_{n-1,n}} \sqrt{\frac{L_1}{C_1}}, \quad (2C)$$

with λ known from (21).

Case D.— C_1 and L_1 given, L' and s free; f_1 and k specified.

This is same as Case C, except that k is specified instead of $f_{n-1,n}$. The solution can be obtained as follows: Substituting

$$L' = sL_1/\lambda$$

from (1) into (19) and solving for λ gives

$$\lambda = \frac{L_1/C_1}{k^2 - L_1/C_1}. \quad (1D)$$

Then D_1 becomes known by means of (11) or (12) or from the curve $n=1$ in Fig. 4. Next, s becomes known from (17):

$$s = D_1/\pi f_1 \sqrt{L_1 C_1}. \quad (2D)$$

Finally, from $L' = sL_1/\lambda$ and (2D) and (1D),

$$L' = \frac{D_1(k^2 - L_1/C_1)}{\pi f_1 \sqrt{L_1 C_1}}. \quad (3D)$$

Thus the final design-formulas are (2D) and (3D), with λ known from (1D) and hence D_1 known from (11) or (12).

Derivations of formulas.

I will now furnish proofs of the above-stated facts and formulas pertaining to the locations of the minor transmitting bands (and the associated attenuating bands) of a loaded line some or all of whose loading is periodic or lumped. For this purpose I will start with the formula given—though in somewhat different notation—by Campbell (Phil. Mag., March, 1903) for the propagation constant

$$\Gamma = A + iB$$

per periodic interval of the loaded line, A and B denoting respectively the attenuation constant and the phase constant (wavelength constant); the aforesaid formula for Γ is

$$\cosh \Gamma = \cosh \gamma + \frac{b}{2g} \sinh \gamma. \quad (22)$$

b denotes the impedance of each loading coil; g and γ pertain to each segment of smooth line between loading coils, g denoting the characteristic impedance, and γ the propagation constant; that is

$$b = R' + i\omega L', \quad (23)$$

$$g = \sqrt{(R_1 + i\omega L_1)/(G_1 + i\omega C_1)}, \quad (24)$$

$$\gamma = s\sqrt{(R_1 + i\omega L_1)(G_1 + i\omega C_1)}, \quad (25)$$

where R' and L' denote the resistance and inductance of each loading coil; and R_1, G_1, L_1, C_1 the resistance, leakance, inductance, capacity, per unit length, of the line segments between loading coils; and i denotes the imaginary operator

$$\sqrt{-1}.$$

As already explained, the frequencies that may properly be regarded as the boundary frequencies of the transmitting bands are the boundary frequencies of the transmitting bands of the corresponding non-dissipative loaded line—that is, of the loaded line for which R', R_1 , and G_1 are zero, so that

$$b = i\omega L', g = \sqrt{L_1/C_1} \text{ and } \gamma = i\omega s\sqrt{L_1 C_1}.$$

The general formula (22) for the propagation constant Γ of the loaded line then reduces to

$$\cosh \Gamma = \cos 2D - \frac{D}{\lambda} \sin 2D, \quad (26)$$

by aid of (1) and (2). This formula (26) can be transformed to the following, which will be found more convenient for certain purposes:

$$\sinh^2 \Gamma = (\sin^2 2D) (D \tan D - \lambda) (D \cot D + \lambda) / \lambda^2 \quad (27)$$

$$= (\sin^2 2D) (D^2 - \lambda^2 - 2D \cot 2D) / \lambda^2. \quad (28)$$

It should now be noted, from (26) and (27), that $\cosh \Gamma$ and $\sinh^2 \Gamma$ are both pure real for a non-dissipative loaded line.

The locations of the transmitting bands 5 will now be found by making a study of

$$\cosh \Gamma = \cosh (A + iB) = \cosh A \cos B + i \sinh A \sin B. \quad (29)$$

In particular, when $\cosh \Gamma$ is pure real—as for a non-dissipative loaded line—the values of A and B must, by (29), be such as to satisfy the pair of equations

$$\sinh A \sin B = 0, \quad (30)$$

$$\cosh A \cos B = \cosh \Gamma, \quad (31)$$

when $\cosh^2 \Gamma < 1$, that is, $\sinh^2 \Gamma < 0$, then $A = 0$ and $B = \cos^{-1} \cosh \Gamma$; (32)

when $\cosh^2 \Gamma > 1$, that is, $\sinh^2 \Gamma > 0$, then $A = \cosh^{-1} |\cosh \Gamma|$ and $B = q\pi$; (33)

- 20 $\cosh \Gamma$ being real, and q being an even or an odd integer according as $\cosh \Gamma$ is positive or negative respectively. From (32) and (33) it is seen that the transmitting bands ($A=0$) are characterized by the inequality $\sinh^2 \Gamma < 0$, and the attenuating bands ($A \neq 0$) by the inequality $\sinh^2 \Gamma > 0$, and hence that the transition points between these two kinds of bands are characterized by the equation $\sinh^2 \Gamma = 0$.
- 25 The transition values of D are the zeros (roots) of the first three factors of the equation (27) for $\sinh^2 \Gamma$. The zeros of the factor $\sin^2 2D$ are at $D = m\pi/2$, with $m = 0, 1, 2, 3, \dots$; thus they subdivide the D -scale into 30 segments of width $\pi/2$ each, as represented by Fig. 3. The zeros of the factors $D \tan D - \lambda$ and $D \cot D + \lambda$ are situated in the odd and even numbered segments respectively because λ , as defined by (1), is essentially positive; there is only one zero in each segment.

- 35 Formulated analytically, with the arguments of the trigonometric functions reduced to the smallest positive values that preserve the values of the functions, the transition values of D are the values of $D_{n,n+1}$ and D_n satisfying the equations

$$\sin^2 2 \left(D_{n,n+1} - n \frac{\pi}{2} \right) = 0, \quad (34)$$

$$D_n \tan \left(D_n - [n-1] \frac{\pi}{2} \right) = \lambda, \quad (35)$$

- 40 with $n = 0, 1, 2, 3, \dots$ in (34) and $n = 1, 2, 3, \dots$ in (35). Equation (34) is equivalent to

$$\sin^2 2D = 0.$$

With n odd and with n even, (35) is equivalent respectively to

$$D \tan D - \lambda = 0$$

45 and to

$$D \cot D + \lambda = 0.$$

equations (26) and (27) so as to determine the D -ranges of no attenuation ($A=0$).

When $\cosh \Gamma$ is known, the components A and B of Γ can be evaluated by means of the identity

10

with, of course, the added restriction that A must be real and positive, and B real. From (30) and (31) it follows that

By inspection of (27) it can be verified that $\sinh^2 \Gamma$ is negative when

$$D_{n-1,n} < D < D_n$$

65

and positive when

$$D_n < D < D_{n,n+1};$$

and hence that these two ranges of D are a transmitting band and an attenuating band respectively, the corresponding compound band thus being the range

$$D_{n-1,n} < D < D_{n,n+1}.$$

75

The values of D_n , namely the roots of (35), cannot be written down directly nor expressed exactly. But they can be found to any desired degree of approximation by first developing the left side of (35) into a power series involving D_n ; and then, by successive approximation or by undetermined coefficients, solving the resulting equation so as to express D_n as a power series in λ —that is, “reverting” the first series to obtain the second. It was in this way that I obtained formulas (10) and (11). (“Reversion” of series by the method of undetermined coefficients is treated in most advanced algebras and in books on the theory of infinite series.) 80 When a more convergent power series than (10) is needed it can be obtained by expanding the original function in the neighborhood of a value of the variable known to be an approximate solution of the equation to be solved, and then reverting the resulting series. However, the formula (12) of successive approximation meets all the needs of numerical evaluation of D_n , for all the values of n —including $n=1$.

The formula (12) of successive approximation can be derived from (35) by application of Newton’s method, which may be

95

100

formulated in general as follows, x denoting the unknown quantity to be evaluated: Let the equation to be solved for x be written in the form

$$5 \quad \phi(x) = 0.$$

Let x_1 denote a known approximate value of x , and h_1 the unknown but small differ-

$$\phi(x_1 + h_1) = \phi(x_1) + h_1 \phi'(x_1) + \frac{h_1^2}{2} \phi''(x_1) + \dots = 0 \quad (36)$$

15 wherein $\phi'(x_1)$, $\phi''(x_1)$, $\dots$ are the first, second, $\dots$ derivatives of $\phi(x)$ with respect to x , evaluated at $x=x_1$. When the terms containing higher powers of h_1 than the first power are neglected, equation (36) 20 yields the following approximation for h_1 ,

$$h_1 = -\phi(x_1)/\phi'(x_1).$$

This approximate value for h_1 when added to the first approximation x_1 for x yields a 25 second approximation for x , namely

$$x_2 = x_1 - \phi(x_1)/\phi'(x_1)$$

in terms of the known quantities x_1 , $\phi(x_1)$, and $\phi'(x_1)$. This step completes the first 30 cycle of the process of successive approximation. The succeeding cycles are similar thereto; thus the second cycle begins with the second approximation x_2 for x , by writing x in the form

$$x = x_2 + h_2$$

and then obtaining an approximate value for h_2 by application of Taylor's theorem to

$$40 \quad \phi(x_2 + h_2) = 0$$

corresponding to equation (36) with x_2 and h_2 corresponding to x_1 and h_1 respectively. In the present application of Newton's method, to the derivation of (12) from 45 (35),

$$x = \tau_n = D_n - d_n,$$

$$\phi(x) = \phi(\tau_n) = (\tau_n + d_n) \tan \tau_n - \lambda.$$

I will now briefly describe several graphical methods which are useful not only for determining approximate values of the internal transition frequencies, but also for verifying readily many of the facts proved analytically above.

55 For the sake of brevity, the graphical methods to be described will be formulated explicitly with reference to the transition values of D instead of the frequency f ; but, by (2), the two are related by the simple equation

$$D = \pi f s \sqrt{L_1 C_1},$$

the transition values of f thus being obtainable by dividing the transition values of D by

$$65 \quad \pi s \sqrt{L_1 C_1}.$$

The various graphical methods for deter-

ence between the unknown exact value of x and the approximate value x_1 , so that

$$x = x_1 + h_1.$$

10

Then an approximate value for the small correction term h_1 can be obtained by application of Taylor's theorem:

$$h_1^2 \phi''(x_1) + \dots = 0 \quad (36)$$

70

mining D_n correspond to the various ways of writing the function

$$(D \tan D - \lambda) (D \cot D + \lambda)$$

75

whose zeros are the values of D_n .

To formulate the graphical methods concisely, let E denote any function of the variable D , so that, geometrically E is the ordinate corresponding to the abscissa D . Six of the various possible graphical methods are then briefly but completely indicated by the following respective statements that the internal transition points D_n are the abscissas of the points of intersection of:

80

1. The horizontal straight line $E = \lambda$ with the curves

$$E = D \tan D;$$

85

the horizontal straight line $E = -\lambda$ with the curves

$$E = D \cot D.$$

90

2. The straight line $E = D$ with the curves

$$E = \lambda \cot D;$$

95

the straight line $E = -D$ with the curves

$$E = \lambda \tan D.$$

100

3. The straight line $E = D/\lambda$ with the co-tangent curves

$$E = \cot D;$$

105

the straight line $E = -D/\lambda$ with the tangent curves

$$E = \tan D.$$

110

4. The hyperbola $E = \lambda/D$ with the tangent curves

$$E = \tan D;$$

115

the hyperbola $E = -\lambda/D$ with the cotangent curves

$$E = \cot D.$$

120

5. The parabola $E = D^2/\lambda - \lambda$ with the curves

$$E = 2D \cot 2D.$$

125

6. The curve $E = D/2\lambda - \lambda/2D$, compounded of the straight line

$$E = D/2\lambda$$

130

and the hyperbola

$$E = -\lambda/2D,$$

135

with the cotangent curves

$$E = \cot 2D.$$

140

Methods 1, 2, 3, 4 follow from the for-

mula for $\sinh^2 \Gamma$ when written in the form (27) or forms obtainable directly therefrom; methods 5, 6 follow from (28).

Some or all of these graphical methods 5 show clearly that:—one and only one transition value of D lies within each of the segments of width $\pi/2$;

10 $\sinh^2 \Gamma < 0$ when $D_{n-1,n} < D < D_n$
and
10 $\sinh^2 \Gamma > 0$ when $D_n < D < D_{n,n+1}$;

15 the zeros of $\lambda - D \tan D$ and of $\lambda + D \cot D$ are situated in the odd and even numbered segments respectively; with increasing D , the transmitting bands continually decrease in width and the attenuating bands continually increase in width, the change taking place rapidly at first and then more and more slowly, increasing λ increases the ratio 20 of transmitting band width to attenuating band width.

25 It will be obvious that the general principles herein disclosed may be embodied in many other organizations widely different 25 from those illustrated without departing from the spirit of the invention as defined in the following claims.

What is claimed is:

30 1. A transmission line having distributed capacity, distributed inductance and lumped inductance, said capacity, distributed inductance and lumped inductance having such relative values with respect to each other as to produce a major band of free transmission 35 extending from zero to a pre-assigned upper cut-off frequency, and said distributed and lumped inductances being so proportioned to each other as to produce a plurality of minor bands of free transmission at successive intervals above said major band and having frequencies low enough to permit of signal transmission without undue attenuation.

40 2. A transmission line having distributed capacity, distributed inductance and lumped inductance, said capacity, distributed inductance and lumped inductance having such relative values with respect to each other as to produce a major band of free transmission 45 extending from zero to an upper cut-off frequency, and said distributed and lumped inductances being so proportioned to each other as to produce a plurality of minor bands of free transmission located at successive intervals above said major band and having frequencies low enough to permit of signal transmission without undue attenuation, said bands being separated from each other by attenuating bands.

50 3. A transmission line having distributed capacity, distributed inductance and lumped inductance, said capacity, distributed inductance and lumped inductance having such relative values with respect to each other as 55 to produce a major band of free transmission

70 sion extending from zero to a preassigned upper cut-off frequency, and said distributed and lumped inductances being so proportioned to each other as to produce a plurality of minor bands of free transmission at successive intervals above said major band and having frequencies low enough to permit of signal transmission without undue attenuation, each of said minor bands being of lesser width than the major band.

75 4. A transmission line having distributed capacity, distributed inductance and lumped inductance, said capacity, distributed inductance and lumped inductance having such relative values with respect to each other as to produce a major band of free transmission 80 extending from zero to a preassigned upper cut-off frequency, and said distributed and lumped inductances being so proportioned to each other as to produce a plurality of minor bands of free transmission at successive intervals above said major band and having frequencies low enough to permit of signal transmission without undue attenuation, each of said minor bands being of 85 narrower than the major band and each minor band being narrower than the next band below it in the frequency spectrum.

90 5. A transmission line having distributed capacity, distributed inductance and lumped inductance, said capacity, distributed inductance and lumped inductance having such relative values with respect to each other, 95 said distributed and lumped inductances being so proportioned to each other as to produce a plurality of adjacent compound bands of equal width, each compound band comprising a band of free transmission and the succeeding attenuating band, said bands of free transmission having frequencies low 100 enough to permit of signal transmission without undue attenuation.

100 6. A transmission line having distributed capacity, distributed inductance and lumped inductance, said capacity, distributed inductance and lumped inductance having such relative values with respect to each other, 105 said distributed and lumped inductances being so proportioned to each other as to produce a plurality of adjacent compound bands of equal width, each compound band comprising a band of free transmission and the succeeding attenuating band, said bands of free transmission having frequencies low 110 enough to permit of signal transmission without undue attenuation, the band of free transmission of each compound band being narrower than the corresponding band of free transmission in the compound band 115 just immediately below it in the frequency spectrum.

120 7. A transmission line having distributed capacity, distributed inductance and lumped inductance, said capacity, distributed inductance and lumped inductance having such 125

70

75

80

85

90

95

100

105

- relative values with respect to each other, said distributed and lumped inductances being so proportioned to each other as to produce a plurality of transmitting bands separated by attenuating bands, said bands of free transmission having frequencies low enough to permit of signal transmission without undue attenuation, the lower limiting frequencies of the free transmission bands being equally spaced, and the ratio of the transmitting band width to attenuating band width increasing as the ratio of the distributed inductance to the lumped inductance increases.
8. In combination with a transmission line having a major band of free transmission and a plurality of minor transmitting bands of lesser width successively located above said major band, a main signaling channel comprising apparatus for transmitting and receiving signals over said major band, and a plurality of carrier channels each comprising carrier transmitting and carrier receiving apparatus having carrier frequencies assigned thereto falling within certain of said minor bands of free transmission.
9. In combination with a transmission line having a major band of free transmission and a plurality of minor bands of lesser width successively located above said major band, a main signaling channel comprising telephone transmitting and receiving apparatus for transmitting voice frequencies within said major band of free transmission, and a plurality of carrier channels each comprising carrier transmitting and receiving apparatus, said carrier channels having assigned thereto carrier frequencies falling within certain of said minor bands of free transmission, and selective means associated with each channel selective of frequencies corresponding to the band of free transmission utilized by the channel.
10. In combination with a transmission line having a major band of free transmission and a plurality of minor bands of lesser width successively located above said major band, a main signaling channel comprising apparatus for transmitting and receiving signals over said major band, a plurality of carrier channels each comprising carrier transmitting and carrier receiving apparatus having carrier frequencies assigned thereto falling within certain of said minor bands of free transmission, and selective means associated with each channel selective of frequencies corresponding to the band of free transmission utilized by the channel.
11. In combination with a transmission line having a major band of free transmission and a plurality of minor bands of lesser width successively located above said major band, a main signaling channel comprising telephone transmitting and receiving apparatus for transmitting voice frequencies within said major band of free transmission, a plurality of carrier channels each comprising carrier transmitting and receiving apparatus, said carrier channels having assigned thereto carrier frequencies falling within certain of said minor bands of free transmission, and selective means associated with each channel selective of frequencies corresponding to the band of free transmission utilized by the channel.

In testimony whereof, I have signed my name to this specification this 8th day of July 1924.

RAY S. HOYT.
